(57) CLAIM

The ornamental design for a hanger for accessories, as shown and described.

DESCRIPTION

FIG. 1 is a front perspective view of a hanger for accessories;

FIG. 2 is a front elevation view thereof;

FIG. 3 is a rear elevation view thereof;

FIG. 4 is a top view thereof;

FIG. 5 is a bottom view thereof;

FIG. 6 is a right side view thereof; and,

FIG. 7 is a left side view thereof.

The broken lines shown represent portions of the hanger for accessories that form no part of the claimed design.
